TOY

Edward Frank Kupka, Mason City, Iowa

Application November 2, 1940, Serial No. 364,081

2 Claims. (Cl. 46—104)

This invention relates to toys and has special reference to a mechanical toy adapted to crawl along a surface such as a floor and simulate the motions of a caterpillar or inch worm.

One object of the invention is to provide a novel toy of this character in which provision is made for the toy to crawl over a surface with its central portion alternately rising in a hump and assuming a straight position between the two ends.

A second important object of the invention is to provide a novel device of this character wherein in the two end portions of the device alternate approach and recede from each other.

A third important object of the invention is to provide a toy of this character wherein the approaching and receding movements above mentioned are effected by alternate forward movement and stoppage of the rear end portion of the device.

With the above and other objects in view, as will be presently apparent, the invention consists in general of certain novel features of construction and combinations of parts hereinafter fully described, illustrated in the accompanying drawings and particularly pointed out in the appended claims.

In the accompanying drawings like characters of reference indicate like parts in the several views, and—

Fig. 1 is a perspective view of the complete toy in one position.

Fig. 2 is a vertical longitudinal section through the toy in a second position, the view being partly in elevation.

Fig. 3 is a plan view of the working parts of the invention with the casing means shown surrounding these parts and in section.

Fig. 4 is an enlarged section on the line 4—4 of Fig. 2.

Fig. 5 is a detail perspective view of a certain guide bracket used herein.

Fig. 6 is a detail perspective view of the front end of a certain operating bar used herein.

In the embodiment shown in the accompanying drawings there is provided a front end casing 10 and a rear end casing 11. Each of these casings is formed of sheet metal or other stiff and rigid material. The casing 10 is of segmento-cylindrical form having a slot 12 formed in its lower rear part and the front end of this casing is closed by a dome shaped portion 13. Similarly the rear casing is slotted as at 14 and has a dome shaped rear closure 15. A lug 16 extends rearwardly from one side of the lower part of the casing 10 and a similar lug 17 extends forwardly

from the lower part of the opposite side of the casing 11. A spring wire helix 18 has its ends fixed in the lugs 16 and 17 and is coaxial with the casings 10 and 11 so that its axis lies above the points of attachment of its ends. By reason of this if the casing 11 be moved toward the casing 10 the helix 18 will bend upwardly.

In the forward end of the casing 10 there is provided a spring motor of ordinary construction the casing of which is shown at 19. The spring motor is provided with a winding shaft 21 which may be wound by means of an ordinary clock key inserted through an opening 22 formed in the casing 10. On the shaft 21 is mounted a sleeve 23 carrying a gear 24. This sleeve is driven by the mechanism (not shown) in the casing 19. Fixed on the shaft 21 is a ratchet 25 which is engaged by a pawl 26 pivotally mounted on the gear 24 to provide the usual ratchet and pawl arrangement for permitting winding of the spring 20 of the motor without affecting the other mechanism of the motor. The motor also includes a governor shaft 27 whereon is mounted a wheel 28 carrying one or more flexible rubber fingers which bend outwardly under centrifugal force 25 upon the wheel 28 rotating rapidly. In the path of the finger is a bracket 30 which is mounted on the member 10 and when the speed of the motor becomes greater than desirable the finger 29 will strike the bracket 30 as it revolves and thus check the action of the motor. The device thus described forms a governor.

A pair of shafts 31 extend across the casing 11 and are journaled in the wall thereof. On the forward shaft 31 is mounted a flanged drum 32 on one of which is arranged a circular series of spaced pins 33 forming a pin gear which meshes with the gear 24 so that the drum 32 is driven by the spring motor. On the rear shaft 31 is mounted a flanged drum 34 and around the drums 32 and 34 is trained a belt 35 having transverse projections 36 simulating caterpillar legs. The lower run of this belt and the projections 36 project downwardly through the slot 12 to engage the surface on which the top rests.

Similarly there is mounted in the rear casing 11 a pair of shafts 37 on which are mounted flanged drums 38 and a belt 39 having projections 40 is trained around the drums. On one of the drums is mounted a ratchet 41 which is engaged by a spring pawl 42, the arrangement being such that the belt can only move in a direction permitting the toy to move forwardly.

Depending from the top of the casing 10 is a pair of brackets 43 which are provided with

openings 44 formed with rearwardly projecting flanges 45. An actuating bar has its forward portion 46 slidably mounted in these brackets and has an enlarged rear portion 47 fixed to the top of the casing 11. A pin 48 extends transversely through the forward end of the bar 46 and limits rearward movement of the bar by engagement with the flanges 45 of the forward bracket 43. A link 49 has its rear end pivoted 10 to the bar 46 and its forward end eccentrically pivoted to the gear 24 so that revolution of the gear moves the rod 46 through the brackets and alternately moves the casing 11 toward the casing 10 and permits the casing 11 to rest while the casing 10 moves forwardly.

An outer cover 50 covers all but the bottom of the device and is suitably decorated to resemble a caterpillar or other similar larva.

In operation the action of the motor drives 20 the forward belt 35 to move the forward end of the toy forwardly at a substantially uniform speed as controlled by the governor at the same time the link 48 alternately effects forward movement and rest of the rear end, the forward movement being faster than the forward movement of the front end. As the rear end moves forwardly it approaches the front end and the spring 18 bends upward to produce the hump common to many insect larva as they move forwardly. As the forward motion of the front end continues the rear end comes to rest and the hump straightens out. Thus operation continues until the motor runs down.

There has thus been provided a simple and 35 efficient device of the kind and for the purpose specified.

It is obvious that changes may be made in the

form and construction of the invention without departing from the material principles thereof. It is therefore to be understood that the invention is not confined to the exact form herein shown and described but it is desired to include 5 all forms which properly come within the scope claimed.

Having thus described the invention, what is claimed as new is:

1. In a toy of the kind described, an elongated 10 hollow body of generally cylindrical form and having rigid front and rear ends and a flexible middle portion, endless belts mounted in and supporting the front and rear ends, motor means actuating the belt in the front section, pawl and 15 ratchet means associated with the rear belt and arranged to prevent backward movement thereof, means actuated by the motor means effecting more alternate movements of the ends toward and from each other and means to effect 20 upward bending of the middle portion during movements of the ends toward each other.

2. In a toy of the kind described, an elongated hollow body of generally cylindrical form and having rigid front and rear ends and having a 25 flexible middle portion, endless belts mounted in and supporting the front and rear ends, motor means actuating the belt in the front section, pawl and ratchet means associated with the rear belt and arranged to prevent backward move- 30 ment thereof, means actuated by the motor means effecting alternate movements of the ends toward and from each other, a spring helix connected below its axis to the lower part of said ends and a flexible cover extending over said 35 ends and helix.

EDWARD FRANK KUPKA.
